D. E. BANGS.
Petroleum-Oil Burner.

No. 227,472.

Patented May 11, 1880.

UNITED STATES PATENT OFFICE.

DAVID E. BANGS, OF MEDFORD, MASSACHUSETTS.

PETROLEUM-OIL BURNER.

SPECIFICATION forming part of Letters Patent No. 227,472, dated May 11, 1880.

Application filed February 27, 1880.

To all whom it may concern:

Be it known that I, DAVID E. BANGS, of Medford, in the county of Middlesex and State of Massachusetts, have invented a new and valuable Improvement in Petroleum-Oil Burners; and I do hereby declare that the following is a full, clear, and exact description of the construction and operation of the same, reference being had to the annexed drawings, making a part of this specification, and to the letters and figures of reference marked thereon.

Figure 1 of the drawings is a representation of a cross-sectional view of my improved oil-burner, and Fig. 2 is a longitudinal section of the same.

This invention has relation to improvements in petroleum-oil burners for heating and cooking purposes; and the nature of the invention consists in the combination, with a reservoir, of an open-ended tube having removable end caps and flame-burners on its top portion, which permits of the burner being cleaned out without its removal.

It also consists in the combination, with a vessel having lamp-cone burners working in connection therewith and slots in its side wall, of removable draft-conducting passages extending through said slots and directing the atmospheric currents to the point of combustion on said burners.

It also consists in a petroleum-burner composed of a vessel having slotted sides, a platform carrying a lamp-cone, a tube extending through the ends of the vessel and provided with burners, and the removable draft-passages extending through the slots of the wall and reaching to the point of combustion of the oil, as hereinafter shown and described.

In the annexed drawings, the letter A designates an oblong metallic vessel having close ends *a*, a bent bottom plate, *b*, and vertical sides *c*, provided with longitudinal slots *s*. The bent bottom plate, *b*, serves to reflect the heat from the burners to the tube C, and assists in vaporizing the oil therein.

Rising from a horizontal platform, *d*, in vessel A is the lamp-cone B, extending from end to end thereof, and having the usual slot *e* at its apex for the passage of the flame.

C indicates a metallic tube extending near the bottom through the ends *a*, and provided

with removable caps *f*. This tube is provided on its top portion with burners *o*, and is connected with an oil-reservoir by means of a pipe, *g*, having at some point in its length, between vessel A and the reservoir, a wire-gauze diaphragm, *i*, that prevents flame from being communicated from the burners *o* to the reservoir when the contents thereof are all fed to the burner.

In practice the reservoir should be higher than the burner, so as to render the feed automatic.

D indicates metallic removable passages, passed sidewise through the slots *s* and terminating inwardly at the burners *o* aforesaid. These passages conduct atmospheric air directly to the point of combustion of the oil, and produce a very strong concentrated draft thereat, which operates, when the draft in the chimney is defective, to produce an intense flame and correct such deficiency; but when the draft in the chimney is strong the sliding passages D may be wholly or partly removed, thus regulating the air-supply with great nicety.

When the reservoir is emptied of petroleum by the feeding of its contents to the burners, coke or a tarry residuum collects in the tube C, which may be cleared out by unskilled labor by removing the caps *f* without detaching the apparatus from the stove.

In practice the vessel A, with its tube C, and, if desired, its platform *d*, may be cast in one piece, and the ends of the tube C should be sufficiently long to reach through the stove-walls, so that it may be cleaned out without removing the device.

The feeding of air direct to the point of combustion insures a very perfect consumption of the carbon and prevents soot from being deposited in the stove and flues.

Having thus described my invention, what I claim as new, and desire to secure by Letters Patent, is—

1. In an oil-burner for cooking and heating purposes, the combination, with a reservoir and an oblong vessel connected therewith and provided with the lamp-cone B, of the tube C, provided with burners *o*, and removable end caps, *f*, and extending through the end walls of said vessel, substantially as specified.
2. The combination, with the vessel A, hav-

ing the lamp-cone B, burners *o*, working in connection therewith, and the slots *s* in its side walls, of the removable draft-conducting slide-passages D, extending through said slots and 5 directing the atmospheric currents to the point of combustion on said burners, substantially as specified.

3. The petroleum-burner consisting of the vessel A, having slotted sides *c*, the platform 10 *d*, carrying the lamp-cone B, the tube C, extending through the ends of the vessel and provided with burners *o* and removable end

caps, *f*, and the removable draft-passages D, extending through the slots of walls *c*, and reaching to the point of combustion of the oil, 15 substantially as specified.

In testimony that I claim the above I have hereunto subscribed my name in the presence of two witnesses.

DAVID E. BANGS.
